UNITED STATES PATENT OFFICE.

WILLIAM E. KURTZ, OF LOS ANGELES, CALIFORNIA, ASSIGNOR TO THE JOHN KRODER & HENRY REUBEL COMPANY, OF BROOKLYN, NEW YORK, A CORPORATION OF NEW YORK.

CURTAIN SUPPORT.

Application filed June 11, 1920. Serial No. 388,194.

To all whom it may concern:

Be it known that I, WILLIAM E. KURTZ, a citizen of the United States, residing at Los Angeles, in the county of Los Angeles and State of California, have invented a certain new and useful Curtain Support, of which the following is a specification.

My invention relates to curtain supports and has for its object to provide a curtain support consisting of a bracket member and a rod member adapted to have a straight, sliding engagement one with the other and provided with interlocking means to prevent accidental separation which preferably are maintained in interlocking relationship by the weight of the rod supplemented by the weight of the curtain supported thereby.

A further object of my invention is to prevent accidental separation of the rod and bracket members by a disengagement of the interlocking means initiated by an upward movement of the rod due to the rebound from a downward pull on the curtain supported by the rod.

A further object of my invention is to provide a curtain support, the bracket members of which are identical, in order to obviate the necessity of right and left members, and the rod member of which can be used either side up or end for end.

Other and further objects of my invention will be apparent from the following description of one embodiment thereof and from the accompanying drawings, in which—

Figure 1 is a perspective of an assembled curtain support of one embodiment of the invention;

Figure 2 a side elevation of the end of a rod member and of a bracket member of the embodiment of Figure 1 in separated relationship;

Figure 3 a plan of parts shown in Figure 2 with the members in assembled relationship;

Figure 4 an enlarged section taken on the line 4—4 of Figure 3 looking in the direction of the arrows;

Figure 5 a view similar to Figure 2 of another embodiment, and

Figure 6 a view similar to Figure 2 of another embodiment.

Similar reference characters refer to similar parts throughout the drawings.

Although the invention is capable of embodiment in many different types of curtain supports and is capable of wide modification in the application of the inventive idea to those types, one type of curtain support and one general application of the invention to that type have been chosen for purposes of illustration.

The type of curtain support chosen for purposes of illustration is the so-called extension curtain support, consisting of a curtain rod having ends extending at right angles to the main body of the rod and supported in horizontal position by the engagement of said ends with brackets secured adjacent the window or other part in front of which the curtain is to hang. The main body of the rod telescopes so that the rod is adapted for windows of varying widths; in other words, the rod can be "extended" to fit wide windows, hence the term extension curtain rod.

Referring to the embodiment of the drawings, an extension or telescoping rod of ordinary type is shown, comprising telescoping portions 1 and 2 having, respectively, right-angled extensions or ends 3 and 4. A slideway of any desired type is provided on each end which may take the form of in-turned edges or flanges 5 and 6 as in Figures 1 to 5, inclusive, of the drawings or of a tubular member 23 as in Figure 6 of the drawings. The slideway is provided with holes or openings (or merely depressions without complete removal of the metal) for interlocking engagement with the bracket members as will appear hereinafter. In Figures 1 to 5, inclusive, of the drawings, holes 7 and 8 are shown for this purpose, and in Figure 6 of the drawings, holes 27 and 28 are shown for a like purpose. As the rod ends are intended to have a straight, sliding movement for engagement with the brackets (as distinguished from a pivotal or turning movement, which necessitates lifting of the rod to engage and disengage it from the brackets, such for example as is shown in patent to Kroder No. 1,196,704, granted August 29, 1916, for extension curtain-rod), the holes preferably are at a substantial distance from the entrance of the slideway.

Each bracket member in the embodiments illustrated is shown as consisting of a base plate 10 provided with any desired means,

as screw or nail holes, for securing it to the wall or window, and a slide piece 11, preferably of substantial length, adapted to slide in the slideway of a rod end. In Figures 1 to 5, inclusive, the slide piece 11 is flat to engage the slideways formed by flanges 5 and 6, while in Figure 6 the slide piece 31 mounted on base 30 is cylindrical to engage the tubular slideway 23. To prevent accidental separation of the rod and bracket members, the slide piece is provided with a pin or key or projection adapted to engage the cooperating hole in the slideway described above. In Figures 1 to 4, inclusive, 10 of the drawings, pins 12 and 13 are shown on the top and bottom of the slide piece and adjacent the end thereof. In Figure 5 of the drawing, the pins 12 and 13 are intermediate the end and base. In Figure 6 of 20 the drawings, pins 32 and 33 are shown as adjacent the ends, but, if desired, may be located as in Figure 5. The location of the pins is not important so long as the straight, sliding engagement of the rod ends and 25 brackets is not interfered with. Each bracket is identical, thereby obviating the necessity of providing right and left members. It also is preferable to have the portion of the slide piece adjacent its bracket 30 the full size of the slideway to insure a close fit, thus necessitating that the slide piece taper in order to provide pins capable of entering in the slideway.

Each bracket can be used on either side of 35 a window and with its base plate 10 turned either in or out. The rod in like manner can be applied to the brackets as is most convenient without the necessity either of determining the proper end for the proper bracket or of turning the rod end for end if the first attempted engagement of the rod with the brackets is not correct.

It is obvious that, if desired, only one hole could be provided in the slideway and only 45 one projection on the slide piece. This would necessitate a selection of the right and left brackets and the application of the rod to the brackets only in one manner. The oppositely positioned holes and pins render the 50 rods and brackets universal in attachment and in use as described above. The oppositely positioned holes and pins also prevent an accidental disengagement of the interlocking holes and pins if the curtain is pulled 55 downwardly and then released, as the rebound will cause an engagement of the lower holes and pins so that the upper holes and pins will engage again when the rod assumes normal position, in which the weight 60 of the rod supplemented by any curtain supported thereby tends to maintain the holes and pins in interlocked relation to prevent separation of the rod and bracket.

The relative location of the slideways and

slide piece may be interchanged within the 65 contemplation of the invention, as it is obvious that the slideways could be located on the bracket and the slide pieces on the rod ends. The pin and hole interlocking arrangement likewise could be reversed with 70 the pin on the slideways and the hole on the slide piece.

Many modifications of my invention will be apparent to those skilled in the art without departing therefrom or from the scope 75 of the claims, my invention not being limited to the embodiments chosen for purposes of illustration, but consisting of a curtain support having rod and bracket members engaging with a straight, sliding movement 80 and maintained against accidental separation by interlocking engagement.

What I claim and desire to secure by Letters Patent is:

1. In a curtain support, a bracket member having a slide piece extending therefrom, a rod member, one end portion of which is telescopically slideable with regard to said slide piece with sufficient play to permit a certain amount of free up and down movement of the rod member when engaging the slide piece, said slide piece and rod end portion having a vertically opposed projection and recess adapted to cooperate to oppose relative sliding between said members when the latter are fully engaged but permitting relative up and down movement therebetween, whereby when said members are so engaged, the above-mentioned play between the bracket and rod permits the latter to move by its own weight to a position in which the projection engages in the recess.

2. In a curtain support, a bracket member having a slide piece extending therefrom, a rod member, one end portion of which is telescopically slideable with regard to said slide piece with sufficient play to permit a certain amount of up and down movement of the rod member when engaging the slide piece, said slide piece and rod end portion having a vertically opposed projection and recess adapted to cooperate to oppose relative sliding between the members when the latter are fully engaged but permitting relative up and down movement therebetween, said projection and recess being located at a substantial distance from the end of the rod when the members are in said last-mentioned position, whereby the rod may tilt downwardly by its own weight when fully engaged, to a position in which the projection fits in the recess.

In testimony that I claim the foregoing, I have hereunto set my hand this 1st day of June, 1920.

WILLIAM E. KURTZ.
